IMPLEMENT POWER HEAD AND HANDLE

John W. Davies, Milwaukee, Wis., assignor to Gilson Brothers Company, Fredonia, Wis., a corporation of Wisconsin

Application November 24, 1958, Serial No. 53,503

Term of patent 14 years

(Cl. D40—1)

Fig. 1 is a perspective view of a combined implement power head and handle embodying my new design.

Fig. 2 is a side elevation thereof.

Fig. 3 is a top plane view thereof.

The motor unit is omitted in Figs. 2 and 3 for convenience of illustration.

The dominant features of the design reside in the portions shown in full lines.

The undisclosed ends of the housing and hood are closed.

I claim:

The ornamental design for a combined implement power head and handle, as shown and described.
